UNITED STATES PATENT OFFICE

ALVIN H. BAER, OF WAYNESBORO, PENNSYLVANIA

COOLING UNIT

Application filed July 28, 1931. Serial No. 553,633.

My said invention relates to a cooling unit for use in reducing the temperature in a household refrigerator, a display case, a refrigerator car or any other of the numerous places where temperature is reduced by such means as ordinary ice or carbonic ice (solid carbon dioxide) which is sometimes known as dry ice. It is an object of my invention to provide a mechanism of this character in which any suitable non-freezing liquid can be used and in which the degree of cooling effect to be transmitted to the refrigerated space can readily be altered without changing the kind or quantity of ice which is used.

Another object of the invention is to provide means for imparting various degrees of refrigeration to a refrigerated space regardless of the temperatures of the ice or other cooling medium which is used in the cooling unit.

Another object of the invention is to provide a very simple and durable type of cooling unit without the use of any machinery excepting in so far as automatic valve controlling mechanism may be utilized, thus avoiding the wear incident to moving parts and also avoiding the necessity of giving attention to the unit, either wholly or at least to a very considerable extent.

Another object of the invention is to provide a unit in which carbonic ice having an evaporating temperature far below freezing can be used without difficulty to cool the refrigerated space only to a relatively slight extent, i. e., to a temperature above the freezing point.

Referring to the drawings, which are made a part of this application and in which similar reference characters indicate similar parts:

Fig. 1 is a plan of my improved cooling unit, partly in section on line 1—1 of Fig. 2,

Fig. 2, an elevation partly in section to show the internal construction,

Fig. 3, a central longitudinal section showing certain parts in a different position, and

Fig. 4, a similar view showing parts in a still different position.

In the drawings there is shown a casing having ends 10 of insulating material or con-

struction and a top 11 similar thereto. In the embodiment of the invention here illustrated the casing is rectangular in horizontal section and has side portions 12 and bottom 13 of heat-conducting material adapted to 55 permit heat from the space to be refrigerated to pass through such portions to the non-freezing liquid inside the casing. A compartment which may be of generally similar form to the casing of the unit is illustrated 60 at 14, this compartment having a lid 15 hinged thereto at 16 and being provided with a lifting handle 17 and locking means comprising a hasp 18 and a bolt 19. The lid may be of any desirable or conventional construction and as here shown includes an upper part hinged to the top 11 and a lower part 20 fitting in the under layer 21 of the top 11, the lower part 20 being smaller than the part 15 to provide a space in which a packing 22 70 may be positioned. Parts 23 extend from the upper part of a wall 12 of the casing to the corresponding wall of the compartment 14 and may be secured thereto by soldering or in any other suitable manner to prevent leakage. 75 As shown in Fig. 1 the casing 12 may also include end members 24 of metal for the same purpose and all these parts may be secured together if desired.

Inside the casing and the ice compartment I 80 have provided partitions of heat-insulating material indicated at 25 alternating with partitions of heat-conducting material indicated at 26. The partitions 26 extend to the upper end of the casing where they may be secured 85 to parts 23 in any suitable manner, while partitions 25 terminate short of the top of the casing. At their lower ends the partitions at each side of the compartment 14 are inclined toward each other so that the partitions 25 next to the ice compartment come into close juxtaposition at their lower ends and similar pairs of the other partitions do the same. Between the juxtaposed lower ends of the pairs of partitions I have located 90 a structure 27 which may be formed in a single piece if desired and which includes forks 28 embracing the lower ends of the partitions or which may be arranged in any other suitable manner to be sufficiently fluid tight 95 100

for my purpose. This structure includes a pair of cylindrical valve casings 29 and 30 in which valves 31 and 32 are mounted for oscillatory movement to a limited extent, 5 here indicated as 90°.

Adjacent to the upper end of each conducting partition 26 I have located a valve casing with an oscillatory valve therein, these casings being indicated at 33, 34, 35 10 and 36. The valves in these casings may be operated by handles 37, 38 as illustrated in Fig. 2 and may be provided with indicators 39, 40 to coact with scales or segmental plates 41, 42. If desired the valves in casings 34 15 and 35 may be connected to valve 31 and the valves in casings 33 and 36 to valve 32 for reasons which will be more fully developed hereinafter. If desired the separate valves or the interconnected valves may be controlled 20 by a thermostat in the refrigerated space, all as is well understood by those skilled in the art, the thermostat being connected to levers such as shown at 37 and 38, and all the valves being provided with such levers or equivalent 25 devices.

The ice compartment is here shown as being provided with a drain passage 43 for carrying off water in case ice is used as the refrigerant and a port 44 for releasing the products of 30 evaporation in case solidified carbon dioxide is used for this purpose. It will be understood that the heat-conducting partitions and the walls of the compartment and the casing may be thin metal walls, whereas the insulating 35 partitions and other insulating portions may be of any conventional or suitable material known to those skilled in the art.

In the operation of my device, if it is desired 40 to create the utmost possible refrigerating effect in the refrigerated space the valve will be positioned as indicated in Fig. 2, so that a current of non-freezing fluid may pass down at either side of the ice compartment 14, then through valves 31 and 32 to the passages 45 lying next to the walls 12, then up along these walls and back across the upper ends of the partitions 25 and through the valves at the upper ends of partitions 26 and so back to the 50 passages lying next to the walls of the compartment for ice or the like. This means that the refrigerated space will be subjected to a current of fluid well chilled by its passage along the walls of compartment 14.

If a lesser degree of refrigeration is desired 55 in the refrigerated space the valve 31 and the valves in casings 34 and 35 may be turned to the position shown in Fig. 3, the valve 32 and the valves in casings 33 and 36 being left in their original positions. The 60 direct passages over the upper ends of the innermost heat-insulating partitions and through valve 31 being now cut off the non-freezing liquid will pass as before down along the sides of compartment 14, will be turned 65 by valve 31 and forced into the passages just

outside said innermost heat-insulating partitions and so back to the innermost passages in a continuous circuit. The fluid in the outer passages next to the walls 12 naturally flows upward as before, due to the heat drawn 70 from the refrigerated space, and passes inward over the upper ends of intermediate heat-insulated partitions, but being prevented from passing over the innermost heat-conducting partitions by the closing of their valves it now passes down along the passages 75 outside these partitions, thence through the side and bottom ports in the valve casing 29, which are now open by reason of the position of the valve 13, then down through valve 32 and back to the outer passages. It will be seen from this that the cold liquid circulating in contact with the walls of the compartment 14 passes upward at one side of the innermost heat-conducting partitions 26 while the circulation established in those passages including the branches next to the wall 12 is passing 80 downward at the same point and a heat exchange takes place through the partitions during such operation. The fluid in the passages adjacent the walls 12 is now however not cooled to the same extent as when the parts are in the position of Fig. 2 and therefore an intermediate rate of cooling action takes 85 place in the refrigerated space.

If a still lower cooling action is desired the valve 32 is also turned through an angle of 90°, as shown in Fig. 4, and the valves in casings 33 and 36 are similarly turned 90° to the upright position shown in Fig. 4. There will now be three different circulations in the unit, one of them being around the innermost heat-insulating partition 25 at each side of the compartment 14. Another circulation takes place about the intermediate heat-insulating wall as indicated by the arrows and heat is abstracted from the fluid in this circulation by the innermost circulation. Still another circulation takes place about the outermost heat-insulating partition at each side of the unit as indicated by the arrows in Fig. 4. The fluid in the innermost circulation is colder than that in the intermediate one and the fluid in the intermediate is colder than that in the outermost one, so that due to the number of transfers of heat and due to the fact that the fluid next to the refrigerated space is at a comparatively high temperature, the cooling effect 100 will be less than in the arrangement illustrated in Fig. 3.

Obviously the number of partitions and valves may be increased to vary still further the cooling effects upon the refrigerated space and the labyrinth formed at each side of the compartment 14 may be varied in this way or in other ways. It should be noted that where a duplex labyrinth is used as here illustrated, a single valve may have a controlling action simultaneously on passages in each labyrinth 105 110 115 120 125 130

by inclining the lower ends of the partitions in the manner illustrated. Obviously a single labyrinth can be used with appropriate valves as illustrated. It will be obvious that the unit must be filled practically to the top with non-freezing liquid in order that circulation may be established as described, this liquid being introduced through any suitable inlet and it will also be obvious that due to the relative temperatures produced by the refrigerant in the compartment 14 and the relatively warm material in the space to be refrigerated, currents will be produced as indicated by the arrows. If greater cooling effect is desired, it may be secured by the use of outside circulation means such as a pump of any suitable well known type for speeding up the circulation.

It will be obvious to those skilled in the art that many changes can be made in the construction illustrated, in the drawings and described in the specification and therefore I do not limit myself to what is shown and described but only as indicated in the appended claims.

Having thus fully described my said invention, what I claim as new and desire to secure by Letters Patent, is:

1. A cooling unit comprising an outer heat-conducting casing, an inner heat-conducting compartment for ice or the like, intermediate partitions respectively of heat-conducting and heat-insulating character providing a labyrinthine passage for non-freezing fluid between adjacent walls of said casing and said compartment, and means whereby circulation may be established either independently in different circuits of the labyrinth including one circuit having a branch along a wall of the compartment and another having a branch along a wall of the casing, the totality of circuits being in heat-exchanging relation, or else a circulation may be established only in the innermost and the outermost branches of the labyrinth and passages leading directly from one to the other, substantially as set forth.

2. A cooling unit as in claim 1, said casing being rectangular in horizontal section and having heat-insulating ends, the partitions extending in parallel relation between said ends and being alternately of heat-conducting and heat-insulating character, substantially as set forth.

3. A cooling unit as in claim 1, said casing being rectangular in horizontal section and having heat-insulating ends, the partitions extending in parallel relation between said ends and being alternately of heat-conducting and heat-insulating character, there being a similar labyrinth at each side of the compartment, substantially as set forth.

4. A cooling unit as in claim 1, said casing being rectangular in horizontal section, and having heat-insulating ends, the partitions

extending in parallel relation between said ends and being alternately of heat-conducting and heat-insulating character, there being a similar labyrinth at each side of the compartment with partitions inclined toward each other at their lower ends to bring corresponding partitions into juxtaposition at their lower ends, and the circulation-establishing means including valves between such juxtaposed lower ends of the partitions whereby one valve serves for controlling circulations in both labyrinths.

5. A cooling unit as in claim 1, said casing being rectangular in horizontal section, and having heat-insulating ends, the partitions extending in parallel relation between said ends and being alternately of heat-conducting and heat-insulating character, there being a group of partitions at each side of the compartment forming substantially independent labyrinths, said partitions being so shaped as to bring correspondingly located ones close together at their lower ends, and valves each in operative relation to the lower ends of a pair of correspondingly located partitions whereby a single valve serves in controlling the circulation in both labyrinths.

6. A cooling unit as in claim 1, said casing being rectangular in horizontal section and having heat-insulating ends, the partitions extending in parallel relation between said ends and being alternately of heat-conducting and heat-insulating character, there being a group of partitions at each side of the compartment forming substantially independent labyrinths, said partitions being so shaped as to bring correspondingly located ones close together at their lower ends, and valves each in operative relation to the lower ends of a pair of correspondingly located partitions whereby a single valve serves in controlling the circulation in both labyrinths, and additional circulation-controlling valves at the upper ends of the heat-conducting partitions, substantially as set forth.

7. A cooling unit as in claim 1, said casing being rectangular in horizontal section, and having heat-insulating ends, the partitions extending in parallel relation between said ends and being alternately of heat-conducting and heat-insulating character, there being a group of partitions at each side of the compartment forming substantially independent labyrinths, said partitions being so shaped as to bring correspondingly located ones close together at their lower ends, and valves each in operative relation to the lower ends of a pair of correspondingly located partitions whereby a single valve serves in controlling the circulation in both labyrinths, and additional circulation-controlling valves at the upper ends of the heat-conducting partitions, said heat-conducting partitions extending to the top of the casing and said

heat-insulating partitions being spaced from said top, substantially as set forth.

8. A cooling unit comprising an outer heat-conducting casing, an inner heat-conducting compartment for ice or the like, partitions between a wall of said casing and a wall of said compartment, providing a labyrinthine passage for non-freezing fluid between such adjacent walls, and means whereby independent circulations may be set up in said passages in varying number and relation, said independent circulations being in heat-exchanging relation and including a branch in a passage along said wall of the compartment and another branch in a passage along said wall of the casing.

In testimony whereof I affix my signature.
